UNITED STATES PATENT OFFICE.

MILTON C. BENHAM, OF ELKHART, INDIANA.

DESIGN FOR A TRAFFIC-GUARD.

59,809.

Specification for Design.

Patented Nov. 29, 1921.

Application filed April 30, 1921. Serial No. 465,848. Term of patent 14 years.

To all whom it may concern:

Be it known that I, MILTON C. BENHAM, a citizen of the United States, residing in the city of Elkhart, county of Elkhart, Indiana, have invented a new, original, and ornamental Design for a Traffic-Guard, of which the following is a specification, reference being had to the accompanying drawing, forming a part hereof.

On the drawing, Figure 1 is a top plan view; Fig. 2 is a side elevation; and Fig. 3 is

a section taken on the line 3—3 of Fig. 2, which views clearly illustrate my new design for a traffic guard.

I claim:

The ornamental design for a traffic guard, as shown.

In testimony whereof I have hereunto affixed my signature this 28th day of April, 1921.

MILTON C. BENHAM.
